Inventor:
Albert Fuldner

UNITED STATES PATENT OFFICE.

ALBERT FULDNER, OF ST. LOUIS, MISSOURI.

BEER-BUNG.

SPECIFICATION forming part of Letters Patent No. 225,515, dated March 16, 1880.

Application filed January 12, 1880.

To all whom it may concern:

Be it known that I, ALBERT FULDNER, of St. Louis, Missouri, have invented a new and useful Improvement in Beer-Bungs; and I do 5 hereby declare the following to be a full and exact description of the same, reference being had to the annexed drawings and letters marked thereon.

This invention relates to an improved bung 10 for beer or other barrels; and it consists in so constructing the body of the bung that after it is put in its place in a barrel it may be transformed into a vent-plug by simply punching through that part of it above a partial vent-hole in the under side, where the said hole is 15 covered with a valve, all of which will be hereinafter more fully described.

Figure 1 represents a cross-section of the bung, showing above it the proper awl to be 20 used. Fig. 2 is also a cross-section, showing the awl as applied. Fig. 3 is an under-side view, showing the film of flexible material.

F represents the bung when first made ready to be placed in a barrel. In the lower or in 25 side is made a hole, A, which may extend nearly through the bung, but leaving sub-

stance enough to sustain the pressure of the liquid within the barrel.

B is a center point exactly in line with the axis of the hole A, so that by forcing the awl 30 E through the wood from B to A a through-vent will be formed in the bung. D is a piece of flexible material sufficiently yielding in its nature to allow the air to pass through the vent A, but to resist the pressure of the gas 35 from within.

The shank of the awl E should be shorter than the thickness of the bung, so that when shoved through the solid part its point cannot reach the valve D. 40

I claim—

A bung, F, for beer or other barrels, having a hole, A, formed therein from the under side, a center point, B, and a flexible valve, D, all constructed substantially as and for the 45 purpose described.

In witness whereof I have hereunto set my hand on this 20th day of December, 1879.

ALBERT FULDNER.
